(57) **CLAIM**

The ornamental design for an exercise attachment, as shown and described.

DESCRIPTION

FIG. 1 is a front perspective view of an exercise attachment, showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front perspective view of the exercise attachment in use.

The dashed broken lines in the figures are for the purposes of illustrating portions of the exercise attachment and form no part of the claimed design.

The dashed broken lines in FIG. 9 show environment and form no part of the claimed design.

1 Claim, 9 Drawing Sheets
